UNITED STATES PATENT OFFICE.

CHARLES H. HILL, OF LYNN, MASSACHUSETTS.

NON-SLIPPING SOLE.

1,049,087.

Specification of Letters Patent. Patented Dec. 31, 1912.

Application filed April 22, 1911. Serial No. 622,776.

To all whom it may concern:

Be it known that I, CHARLES H. HILL, a citizen of the United States of America, residing at Lynn, in the county of Essex and 5 Commonwealth of Massachusetts, have invented certain new and useful Improvements in Non-Slipping Soles, of which the following is such a full, clear, and exact description as will enable others versed in the 10 art to which it appertains to make and use my said improvements.

My invention relates to soles, made from rubber or other suitable material, and intended to be used upon shoes or other surfaces 15 requiring a non-slipping surface, and has for its objects to provide a suction cup at the shank portion of the sole by means of exterior raised reinforcing sections, said 20 suction cup being intended to work in conjunction with accompanying non-slipping surfaces of the tread and heel portions, and to attain other advantages and results, some of which may be hereinafter referred to in connection with the following 25 description.

I attain the object of my invention as shown in the accompanying drawings, in which—

Figure 1 is a bottom view of my improved sole. Fig. 2 is a cross section of the 30 shank portion on the line A—A in Fig. 1.

Similar letters refer to similar parts throughout the several views.

In Fig. 1, B represents the semi-spherical 35 projections which form my non-slipping surface. It will be especially noted that no series of these projections form a straight line in any direction. It is by means of this feature that I insure an efficient clinging 40 surface. It will also be readily seen that these semi-spherical projections with the incidental depressions between the same naturally create a suction when in contact with a wet, slippery and muddy surface.

To insure sufficient holding surface for 45 the stitching D, by which the sole is fastened to the shoe, the longitudinal edges of

the shank are reinforced, as at C, C, said reinforcements being flat on their outer surfaces, as shown in Fig. 2, so as to contact 50 squarely with soft or muddy ground in walking. Between said reinforcements C, C, the shank is cut away, to form a vacuum-cup E, the boundaries of which are the reinforcements C, C, the transverse rear edge 55 of the tread and the transverse front edge of the heel. This construction is valuable, because it renders the sole soft and pliable at the shank, and provides a suitable reinforcement for the stitched portions, and also 60 affords a suction-hold, so much desired during wet and slippery walking.

Having thus described my invention what I claim as new and desire to secure by Letters Patent is:

1. In a shoe-sole provided with a tread and heel, a pliable shank provided, on its longitudinal edges, with reinforcements, each having a flat outer surface to contact 70 squarely with muddy or soft ground in walking, said shank being provided with a cut-away portion, the boundaries of which are the said reinforcements, the transverse rear edge of the tread and the transverse front edge of the heel.

2. In a shoe-sole provided with a tread and heel, both carrying anti-slipping means, a pliable shank provided, on its longitudinal edges, with reinforcements, each having a flat outer surface to contact squarely with 80 muddy or soft ground in walking, said shank being provided with a cut-away portion, the boundaries of which are the said reinforcements, the transverse rear edge of the tread and the transverse front edge of 85 the heel.

In testimony whereof I hereunto affix my signature in the presence of two attesting witnesses.

CHARLES H. HILL.

Witnesses:

CHARLES W. LOVETT,
GEO. C. HERBERT.
